Theodor W. Bean

UNITED STATES PATENT OFFICE.

THEODORE W. BEAN, OF NORRISTOWN, PENNSYLVANIA.

MACHINE FOR ROLLING CAR-WHEELS.

SPECIFICATION forming part of Letters Patent No. 337,230, dated March 2, 1886.

Application filed November 5, 1885. Serial No. 181,873. (No model.)

To all whom it may concern:

Be it known that I, THEODORE W. BEAN, of Norristown, county of Montgomery, and State of Pennsylvania, have invented an Improvement in Machines for Rolling Car-Wheels, of which the following is a specification.

My invention has reference to the manufacture of car-wheels; and it consists in suitable apparatus for rolling and compressing a cast or forged wheel or other similar object into a finished condition, all of which is fully set forth in the following specification, and shown in the accompanying drawings, which form part thereof.

15 Car-wheels as heretofore commonly constructed have been made of cast-iron with chilled surfaces, or of cast-iron and paper combined. A cast-iron wheel, owing to the low strength of cast-iron, must be made excessively heavy to withstand the wear and tendency to breakage. To increase this strength near the hub, it is customary to form two webs uniting near the flange and formed with a hollow space between them, which, while it increases the 20 strength, forms the equivalent of a sounding-box and creates a great deal of noise. The enormous weight of the wheel, aside from the objectionable noise it creates, produces a great deal of unnecessary wear upon the rails, causing 25 their unnecessarily quick destruction. In addition to the foregoing, a cast-iron car-wheel must be constantly watched by tapping to ascertain whether there is any breakage or cracking, and from the enormous quantity of 30 metal used, as well as the chilling required, a cast-iron car-wheel is very expensive.

The object of my invention is to provide suitable apparatus by which a previously cast or forged cast-steel car-wheel may be rotated 35 and compressed into the required shape and give the desired finish, thus obviating the necessity of subsequent handling and treatment. By this means I am enabled to make a most perfect and cheap car-wheel, and from the 40 fact that steel has such an enormous strength I am enabled to produce a car-wheel of very light weight and embodying much greater strength than is possible in the commercial cast-iron car-wheel. In addition thereto, such a cast- 45 steel car-wheel has a much longer life; in ro-

tating creates but very little noise; owing to its construction, it has lightness, and the extreme density of the metal used, and it being pressed into shape, requires no finish or turning, such as required upon cast-iron car-wheels. 55 From the lightness of the wheel, due to the small relative amount of metal required, and from the fact that it can be given a highly-finished surface in the dies, this car-wheel, while being so superior to a cast-iron car-wheel, is, 60 nevertheless, much cheaper. Its lightness increases its own life, as well as that of the rails, and there is no necessity for a continual examination of the wheels, as is now the case.

In the drawings, Figure 1 is a sectional elevation, on line xx , of a rolling-mill for rolling car-wheels and similar articles; and Fig. 2 is a plan view of same.

A is the plate. B is the housing. E is the receiving die or form, and J are the compressing-rollers. The die E has its upper face depressed, as at H, for the reception of the cast-steel ingot I, which in the drawings is shown as a car-wheel; but in practice the rolling-mill is suitable for any form of similar 75 cylindrical and disk-shaped objects, and this die is supported upon anti-friction balls D, which are placed in annular grooves C, and may be pivoted, as at e. In place of the balls D, suitable supporting-wheels may be employed, as such are considered equivalents. 80

The die E is provided with gear-teeth F, with which a pinion, G, meshes and by which it is rotated. The said pinion being revolved by the power-shaft g for car-wheels, there 85 would be a central stud, h, around which the car-wheel would be rolled, and which would form the hole for the reception of the axle.

N is a roll-carrying frame, and may be raised and lowered by a screw, O, which 90 works through the upper part of the housing B. This frame N is prevented from turning by guide-lugs n, and its lower and central part is provided with a stud, M, to which a ring, l, is journaled, and from which the three 95 shafts or bearings I extend, preferably somewhat obliquely upward, and are secured at their outer ends to the frame N. Journaled upon these shafts I are rollers J, whose peripheries are made to conform to the shape to 100

be given to the object to be rolled. These rolls are preferably formed more or less conical, and may be made in one or several sections, the latter being indicated at K, Fig. 1, 5 so that each section may revolve independent of the other, to reduce as much as possible the tendency to rubbing. The outer ends of these rolls are formed with the cutting-edge *k*, for the purpose of trimming the outer flange of 10 the wheel after the metal has been rolled from the center outward. Three rollers are shown, though it is evident that one or more may be used.

The cast-steel ingot, before being placed in 15 the die E, is previously heated, thus reducing the metal to a state in which it is easily caused to flow under pressure, and whereby the rolling action is facilitated.

Having now described my invention, what 20 I claim as new, and desire to secure by Letters Patent, is—

1. In a rolling-mill, the combination of the revolving die E, having its upper surface formed to receive the previously-cast article 25 to be rolled, with a stationary frame, N, and loose compressing-roller J, journaled therein, substantially as and for the purpose specified.

2. In a rolling-mill, the combination of the revolving die E, having its upper surface 30 formed to receive the previously-cast article to be rolled, with a stationary frame, N, and loose compressing-roller J, journaled therein, suitable guides to prevent said frame from revolving, and screw O, to raise or lower the said 35 frame and its roller, substantially as and for the purpose specified.

3. In a rolling-mill, the combination of the revolving die E, having the part H, to receive the article to be rolled, and gear-teeth F, with pinion G, anti-friction balls D, stationary 40 frame N, carrying the rollers J, suitable guides or stops to prevent said frame from revolving, and screw O, to adjust said frame vertically, substantially as and for the purpose specified.

4. In a rolling-mill, the combination of the 45 revolving die E, having its upper surface formed to receive the previously-cast article to be rolled, with a stationary frame, N, and loose compressing-roller J, journaled therein, the said rolls being made more or less conical and formed in sections K, substantially as 50 and for the purpose specified.

5. In a rolling-mill, the revolving die E, having its upper part formed at H to conform to the shape of one side of a car-wheel, and provided 55 with stud h, in combination with stationary rollers J, extending from the center of the die outward, and having their peripheries so shaped as to form the other face of the car-wheel, and a frame or support for said rollers, to prevent 60 their rotation about the studs h, and feeding devices, substantially as described, to move said rollers to or from the die E, substantially as and for the purpose specified.

In testimony of which invention I hereunto 65 set my hand.

THEO. W. BEAN.
